US0D1000448S

(12) **United States Design Patent** (10) **Patent No.:** **US D1,000,448 S**
(45) **Date of Patent:** ** **Oct. 3, 2023**

(54) **STAND FOR A DEVICE**

(71) Applicant: **Amazon Technologies, Inc.**, Seattle, WA (US)

(72) Inventors: **Monica Liane Mecchella**, San Francisco, CA (US); **Gregory Marecek**, Millbrae, CA (US)

(73) Assignee: **Amazon Technologies, Inc.**, Seattle, WA (US)

(**) Term: **15 Years**

(21) Appl. No.: **29/724,769**

(22) Filed: **Feb. 19, 2020**

Related U.S. Application Data

(60) Division of application No. 29/628,191, filed on Dec. 1, 2017, now Pat. No. Des. 879,106, which is a continuation of application No. 29/619,025, filed on Sep. 26, 2017, now abandoned.

(57) **CLAIM**

The ornamental design for a stand for a device, as shown and described.

DESCRIPTION

FIG. 1 is a top perspective view of a stand for a device;

FIG. 2 is a front view thereof;

FIG. 3 is a back view thereof;

FIG. 4 is a left-side view thereof;

FIG. 5 is a right-side view thereof;

FIG. 6 is a top view thereof; and

FIG. 7 is a bottom view thereof.

The broken lines depict portions of the stand for a device that form no part of the claimed design.

1 Claim, 7 Drawing Sheets
